UNITED STATES PATENT OFFICE.

STUART W. PARSONS, OF NEW BRITAIN, CONNECTICUT, ASSIGNOR TO THE STANLEY WORKS, OF NEW BRITAIN, CONNECTICUT, A CORPORATION OF CONNECTICUT.

DOOR CATCH.

Application filed September 12, 1924. Serial No. 737,295.

This invention relates to door catches of the sort having a lever pivoted between its ends, one end of the lever being in the path of the door to check the closing movement thereof and thereby prevent the door from slamming noisily or violently, and the other end of the lever being adapted to engage the outside of the door to complete its closing movement and to hold the door in tightly closed position, a spring being associated with the lever so as to throw the same to its extreme positions. Door catches of this sort are used in connection with spring closed doors such as, for instance, screen doors.

The aim of the invention is to provide a door catch of this sort having various features of novelty and advantage, and which is particularly characterized by its neat and pleasing appearance, by its simplicity in construction and economy in manufacture, and by its durability and effectiveness in operation.

Other objects will be in part obvious and in part pointed out more in detail herein-after.

The invention accordingly consists in the features of construction, combination of elements and arrangement of parts which will be exemplified in the construction herein-after set forth, and the scope of the application of which will be indicated in the appended claims.

In the accompanying drawings, wherein I have shown, for illustrative purposes, one embodiment which the present invention may take:

Figure 1 is a top plan view of the device associated with a door shown in horizontal section;

Fig. 2 is a front elevation thereof;

Fig. 3 is a view taken longitudinally and centrally through the device, the lever being shown in door checking position;

Fig. 4 is a transverse sectional view taken substantially on line 4—4 of Fig. 1; and

Fig. 5 is an elevational view of the member to which the spring is anchored.

Referring to the drawings in detail, A denotes a casing or support; and B, a lever pivoted between its ends to the support and having at one end a roller C which the door is adapted to strike as it swings into closing position, as shown most clearly in Fig. 3. The other end of the lever carries a roller D adapted to engage the outside of

the door to complete the closing movement thereof and hold the same tightly closed. E is a spring connected at one end to the lever B and at the other end to a bracket or anchor F and so arranged as to snap the lever to each of its extreme positions. The letter G designates rivets which connect the bracket F to the support A. In Fig. 1, the support A is shown as being secured to a door casing H adjacent the swinging or free edge of the door, the latter being designated by the letter I.

The support A is preferably formed of sheet metal by stamping out a blank of the desired configuration and then bending and drawing the blank to the shape shown. The support is generally U-shaped in section and has generally parallel side walls 10 and a connecting or end wall 11, the latter being longitudinally curved to correspond generally to the longitudinal curvature of the lever B. The support may be secured to the door casing in any suitable manner and, to this end, it may be provided with flanges 12 apertured to accommodate securing screws 13. The forward or outer end of the support is provided with aligned apertured bosses 14 which, together with complementary bosses 15 on the bracket F, constitute bearings for the lever B. The bosses 14 and 15 are preferably formed by punching holes in the metal and bending the metal about the holes outwardly or inwardly, as the case may be. The openings 16 in the bosses 14, and the corresponding openings 17 in the bosses 15, are non-circular. They are, preferably, square, as shown, and the rivets G are likewise square so as to prevent relative movement between the bracket F and the support. The bracket F, which is also, by preference, constructed of sheet metal stamped and bent to proper shape, is in the form of a U or yoke, and the connecting portion 20 of the yoke is provided with an apertured tongue 21 to which is attached one end of the spring E.

The lever B, which is, preferably, formed of a single piece of sheet metal, is longitudinally curved so that it is somewhat crescent shaped. As previously stated, the longitudinal curvature of the lever corresponds generally to the curvature of the end wall 11 of the support so that the device presents a neat and pleasing design. The lever B is also transversely curved, that is to say, it is

2
generally U or channel shaped in cross section. The side (i. e. top and bottom) walls of the lever are designated by the numeral 25, and the front wall by the numeral 26. 5 The side walls are provided with aligned apertures 27 which receive the bearings formed by the cooperating bosses 14 and 15. The roller C is preferably formed of resilient material, such as rubber, and is journaled on a shaft 28 carried by ears 29 extending from one end of the lever. The roller D is similarly journaled on a shaft 30 carried by ears 31 at the other end of the roller. At that end of the front wall 26 10 adjacent the roller D is a backwardly turned tongue 33 which is suitably apertured to receive the hook on one end of the spring E, as shown most clearly in Fig. 3.

The operation of the device is briefly as 20 follows: When the door I is swung open, it initiates movement of the lever B from the position shown in Fig. 1, and, after the spring has been thrown past dead center, it snaps the lever to the position shown in Fig. 25 3. When the door is swung into closed position, it engages the roller C, as shown in Fig. 3, whereupon the closing movement of the door is checked and violent slamming thereof is avoided. The door, continuing 30 its closing movement, will swing the lever counter-clockwise and, after the spring has been thrown past dead center, it will snap the lever to the position shown in Fig. 1, thus insuring that the door will be brought 35 to fully closed position and held in that position.

It will be observed, and particularly from Fig. 2, that when viewing the device in front elevation, the spring E and the bracket F 40 are entirely concealed by the lever B and that that end of the lever carrying the roller C is housed within and concealed by the support A. Thus, there is only exposed to view the rounded portion of the lever, the support A, and a portion of the roller D. The lever B which, by preference, is one 45 integral piece, may be very cheaply manufactured from wrought sheet metal, the use of separate plates and pins or cross struts 50 for holding the plates together being entirely eliminated. The bearings for the lever are cheaply formed, the parts of the bearings may be readily assembled together, and wear upon the bearings is negligible. 55 As previously pointed out, the member F, in addition to constituting, in part, bearings for the lever, also serves as an anchor for one end of the spring E. The structure 60 comprises but relatively few parts, each of which may be manufactured at a relatively low cost, the parts may be readily assembled together, and these parts are particularly strong and durable so that the catch will have a relatively long life.

65 As many changes could be made in the

above construction and many apparently widely different embodiments of this invention could be made without departing from the scope thereof, it is intended that all matter contained in the above description or 70 shown in the accompanying drawing shall be interpreted as illustrative and not in a limiting sense.

It is also to be understood that the language used in the following claims is intended to cover all of the generic and specific features of the invention herein described and all statements of the scope of the invention which, as a matter of language, might be said to fall therebetween. 80

I claim as my invention:

1. In a device of the character described, a support, a longitudinally curved lever pivoted between its ends and having a front wall, and a spring connected to said lever 85 for throwing the same into each of its extreme positions, said front wall extending beyond each end of said spring and said spring being positioned behind said wall, whereby said spring is concealed from front view by said front wall when said lever is in door holding position. 90

2. In a device of the character described, a support, a sheet metal lever curved longitudinally and generally channel shaped, in cross section and pivoted between its ends on said support, a spring anchor carried by said support, and a spring connected at one end of said lever and at the other end to said anchor, said lever having its front wall extending beyond each end of said spring and said anchor being between the ends of said front wall whereby said spring and anchor are concealed from front view by said lever when the latter is in door holding position. 100

3. In a device of the character described, a sheet metal support having a pair of side walls and an intermediate connecting wall longitudinally curved, a sheet metal lever 110 longitudinally curved corresponding to the curvature of said connecting wall, said lever having side walls pivoted to the side walls of said support and a front wall between the side walls, one end of said lever being housed within and concealed by said support when the lever is in door holding position, and a spring connected to said lever behind the front wall thereof for throwing the same into its extreme positions, said front wall extending beyond each end of said spring. 115

4. In a device of the character described, a support provided with side walls, a lever having side walls fitting within the side walls of said support, rivets passing through the corresponding side walls of said support and lever, a spring anchor fixed to said rivets, and a spring connected at one end to said lever and at its other end to said anchor. 125

5. In a device of the character described, a support provided with side walls having aligned non-circular apertures, a U-shaped member having its ends provided with non-circular openings registering with those in the said side walls, rivets fitting in said non-circular openings and securing said member against movement, a sheet metal lever having side walls journalled between the side walls of said support and the ends of said member, and a spring connected at one end to said lever and at its other end to said member.
10. In a device of the character described, a support provided with side walls, a member positioned between said walls and having, adjacent its ends, cylindrical bearings, rivets extending through said side walls and said bearings, a sheet metal lever channel shaped in cross section and having its side walls journalled, on said bearings, and a spring between said member and lever.
15. In a device of the character described, a support provided with side walls, a lever having side walls fitting within the side walls of said support, a member carried by and fixed against movement relative to said first side walls and extending therebetween, said side walls of said lever having bearings on said member, and said member having its central portion offset from said bearing, and a spring connected at its opposite ends to said offset and lever.
20. In a device of the character described,
25. a support having side walls provided with apertured inwardly extending bosses, a member provided with apertured outwardly extending bosses adapted to cooperate with said first mentioned bosses to constitute bearings, rivets passing through the respective bosses and securing said member against movement relative to said support, a lever provided with side walls journalled on said bearings, and a spring between said lever and member.
30. 8. In a device of the character described, a support provided with side walls, a lever having side walls fitting within the side walls of said support, a member carried by and fixed against movement relative to said first side walls and extending therebetween, said side walls of said lever having bearings on said member, and said member having its central portion offset from said bearing, and a spring connected at its opposite ends to said offset and lever.

STUART W. PARSONS.
